Fig. 1

Fig. 2

Fig. 3

Figure 1 is a front elevational view of a water heater control embodying our new design;

Figure 2 is a top plan view of the water heater control; and

Figure 3 is a vertical sectional view of the front cover plate of the water heater control.

The back of the water heater control is of conventional construction.

The dominant features of the design reside in the portions shown in full lines.

We claim:

The ornamental design for a water heater control, substantially as shown and described.
